ONE-PIECE CYLINDER LAP TOOL

Carl Young, Anniston, Ala., assignor to EDI
Corporation, Talladega, Ala.

Filed Mar. 6, 1975, Ser. No. 556,051

Term of patent 14 years

Int. Cl. D15—09

U.S. Cl. D37—1 R

FIG. 1

FIG. 2

FIG. 3

FIG. 4

FIG. 5

FIG. 6

FIG. 7

FIG. 8

FIGS. 1 and 5 are perspective views of two species of one-piece cylinder lap tools, showing the single inventive concept of my new design;

FIGS. 2 and 6 are respective front elevational views of this design;

FIGS. 3 and 7 are typical side elevational views;

FIGS. 4 and 8 are respective bottom plan views.

I claim:

The ornamental design for a one-piece cylinder lap tool, as shown.
